UNITED STATES PATENT OFFICE

99,199

DESIGN FOR A GLOVE

Charles R. Kovar, Richmond Hill, N. Y.

Application November 14, 1935, Serial No. 59,549

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 of the drawing are respectively front and back views of a glove showing my new design.

The entire exposed surface of the glove is covered with a number of minute projections formed in the knitted fabric of which the glove is made. The design is further characterized by a relatively narrow cuff trimmed with three similar strips of braided tape attached to each other by open-work stitching.

I claim:

The ornamental design for a glove, as shown and described.

CHARLES R. KOVAR.
